UNITED STATES PATENT OFFICE.

EDWARD BRADFORD JAMES, OF THOMASVILLE, GEORGIA.

PLOW.

SPECIFICATION forming part of Letters Patent No. 363,646, dated May 24, 1887.

Application filed November 10, 1886. Serial No. 218,471. (No model.)

To all whom it may concern:

Be it known that I, EDWARD BRADFORD JAMES, of Thomasville, in the county of Thomas and State of Georgia, have invented a new and 5 Improved Plow, of which the following is a specification, reference being had to the annexed drawings, forming a part thereof, in which—

Figure 1 is a side elevation of my improved plow. Fig. 2 is a plan view of the end of one of the beams, showing the arrangement of the clevis for a single plow. Fig. 3 is a vertical section taken on line $z-z$ in Fig. 1. Fig. 4 is a plan view of the beams, showing the connecting device. Fig. 5 is a front elevation of the plow-standard. Fig. 6 is a plan view of one of the braces; and Fig. 7 is a front elevation of a standard adapted to holding ordinary plows.

Similar letters of reference indicate corresponding parts in all the views.

The object of my invention is to provide a plow which may be arranged as a double plow, or two single plows which may be adjusted to 25 plow two furrows of different depths simultaneously, and which may be used as a cultivator.

My invention consists in the combination, with two plow-beams and adjustable fastening- 30 devices for connecting the beams, of standards pivoted to the beams and supported by offset braces; also, in the combination, with the handles of the plow, of an adjustable support for holding the handles at different heights, 35 all as hereinafter more fully described.

The beams $A A'$ are each provided with right-angled irons $a b$, for connecting the two beams together. The irons a of the beams are clamped to the outer sides of the beams 40 and are arranged to overlap each other in the grooved iron plate B , the irons being provided with several apertures for receiving the shank c of the clevis d , which passes through the plate B and through the iron a , and receives the nut e , by which the irons a and plate B are 45 clamped securely together. The angled irons b , which are employed to connect the opposite ends of the beams $A A'$, are secured to the inner faces of the beams by bolts f and overlap each other, and are clamped together by a 50 bolt, g , extending through apertures in the

angled irons and through a grooved plate, B' , embracing the edges of the irons. By means of these devices the beams $A A'$ may be clamped in any desired position relative to each other, 55 and the clevis d may be adjusted along the angled irons a to regulate the draft.

To the outer side of the beam A' is pivoted the standard C , to which is attached the landside D of the mold-board E . The standard C 60 is braced by the curved bar F , which is pivoted to the standard, near the mold-board and is offset, as shown in Fig. 6, to permit of pivoting it to the outer side of the standard and clamping it to the side of the beam A' without the necessity of cutting into the beam for the reception of the standard C . The upper end of the bar F is curved and provided with series of apertures h , and the said bar is held in position against the beam A' by the yoke i , 70 which is apertured to receive the bolt or pin passing through the apertures h of the bar F .

To the outer side of the beam A is pivoted a similar standard, C' , supported by the bar F' in the manner already described. The standards $C C'$ may be adjusted with the mold-boards and landsides oppositely arranged with respect to each other, or the mold-boards and landsides of the two plows may be arranged in the same direction.

To the rear end of each of the beams $A A'$ is secured an inclined arm, G , having near its upper end a slot for receiving the bolt j of the clamp k , which holds the cross-arm H to the arm G . This arrangement permits of adjusting the handles at different heights to accommodate different persons. To the outer sides of the beams $A A'$ are pivoted the lower ends of the handles I , whose upper ends are apertured to receive the tenons l on the ends of the 85 cross-piece H .

By loosening the plates $B B'$ the angled irons $a a$ and $b b$ may be slid upon each other to adjust the distance between the plow-stands $C C'$, and by shifting the clevis d in one 95 direction or the other the draft of the plow may be adjusted.

The beam A may be detached from the beam A' , leaving an ordinary single plow drawn forward by the clevis d , secured to the angled 100 iron a of the beam A' . When used as a double plow the arms G are placed over the slots m

in the arms H, as shown in dotted lines in Fig. 3, the slots admitting of the lateral adjustment of the beams A A'. When used as a single stock the arm G is placed in the center 5 of the cross-arm H.

By providing an extra pair of handles the double plow may be readily converted into two single plows in the manner already described.

10 The beams may be made to carry plows of different sizes and also of different heights, thus making two furrows simultaneously, one deeper than the other; or the mold-boards may be arranged to face each other, when the plow 15 will be used as a cultivator.

Having thus fully described my invention, I

claim as new and desire to secure by Letters Patent—

The combination, in a plow, of the beams A A', adjustably secured together by the angle-plates a b and coupling-plates B B', the slotted standards G, the cross-arm H, adjustably secured to the standards, having slots m and a central perforation, and the handles I, whereby provision is made for converting the 25 plow into a single or double beam plow, as specified.

EDWARD BRADFORD JAMES.
